TRAVELER

William Wesley Bassett, Pawtucket, R. I., assignee
or to A. E. Carter, Incorporated, Gastonia, N. C.,
a corporation of North Carolina

Application April 10, 1937, Serial No. 136,101

5 Claims. (Cl. 118—61)

This invention relates to ring travelers for spinning machines.

Ring travelers when in operation on a spinning machine travel at a very fast rate of speed around 5 the ring and when so traveling the traveler floats or has practically no contact with the ring.

Various travel cross-sections have been proposed and used, such for instance as round, flat and half-oval, that is oval on one side and flat on 10 the other.

This invention has for its salient object to provide a traveler so designed as to cross-section as to reduce the friction of the yarn on the traveler to a minimum.

15 Another object of the invention is to provide a traveler having a cross-section so designed as to reduce to a minimum the air resistance on the traveler.

Another object of the invention is to provide a 20 traveler so designed as to cross-section as to equalize the weight, thereby producing a more perfect balance.

Further objects of the invention will appear 25 from the following specification taken in connection with the drawing which forms a part of this application and in which

Fig. 1 is a sectional elevation of a traveler ring having mounted thereon one form of traveler constructed in accordance with the invention, and

30 Fig. 2 is an enlarged transverse sectional elevation of the traveler.

In the embodiment of the invention illustrated in the drawing there is shown a traveler 10 which may be of any desired form or shape and in the 35 form illustrated has hooks 11 and 12 formed on the ends thereof for embracing the spinning ring 13. The yarn Y is shown as leading downwardly to the ring 10, passing under the angular portion 15 of the ring and being led to the bobbin or 40 spool S.

The particular novel feature of the traveler consists in the cross-section which is shown in the enlarged view in Fig. 2. From this figure it will be noted that the surfaces 20 and 21 of the 45 traveler are curved or convex and meet at the edges 23 and 24 in lines which lie in the plane of the major axis of the cross-section. It will also be noted that the central portions 30 and 31 of the cross-section are flat.

50 The yarn Y approaches the traveler from an angle and engages one of the convex surfaces 20 or 21 and passes around and across the flat surface 30 or 31, leaving the traveler curved or convex adjacent the other edge of the traveler.

There is a minimum amount of frictional engagement between the yarn and the traveler, and furthermore the air resistance to the movement of the traveler around the ring will be reduced to a minimum. Moreover, the traveler is symmetrical with reference to the major axis which passes through the meeting points of the oval or curved portions 20 and 21.

If desired, the edges of the traveler or ends of the oval surfaces shown at 23 and 24 may be 10 slightly rounded instead of sharp.

Although one specific embodiment of the invention has been particularly shown and described, it will be evident that modifications and changes in the construction may be made without departing from the spirit and scope of the invention, as expressed in the following claims.

Having thus described my invention, what I claim is:

1. A ring traveler having means for embracing a traveler ring and having a double convex cross section at the edges of the traveler, the central portions of the cross section being flat, the cross section being symmetrical with reference to a line passing through the two edges. 20

2. A ring traveler having means for embracing a traveler ring and having a double convex cross section at the edges of the traveler, the central portions of the cross section being flat, the cross section being symmetrical with reference to a line 25 passing through the two edges. 30

3. A ring traveler having means for embracing a traveler ring, said traveler being flat at the central portion of the cross section and curved at the outer ends of the cross section, the cross section being symmetrical with reference to a line 35 passing through the two edges of the traveler.

4. A ring traveler having means for embracing a traveler ring, said traveler being flat at the central portion of the cross section and curved at the outer ends of the cross section, said curved portions meeting at the two edges in lines and being symmetrical with reference to a line passing through the two edges. 40

5. A ring traveler having means for embracing a traveler ring, said traveler being flat at the central portion of the cross section and curved at the outer ends of the cross section, said curved portions converging toward the edges of the traveler and being symmetrical with reference to a line 45 passing through the two edges of the traveler. 50

WILLIAM WESLEY BASSETT.
